UNITED STATES PATENT OFFICE

ALBERT R. BRADEN, OF BEVERLY, MASSACHUSETTS, ASSIGNOR TO UNITED SHOE MACHINERY CORPORATION, OF PATERSON, NEW JERSEY, A CORPORATION OF NEW JERSEY

METHOD OF MAKING DIES

Application filed April 17, 1929. Serial No. 355,923.

My invention relates to die-making, having particular reference to the manufacture of clicking dies for cut-out work.

In pumps or like footwear, a common practice is to produce, in a vamp or other part, a design formed by a combination of perforations. The perforating portions of dies for this purpose, so far as I am aware, have heretofore been machined from a solid piece of tool-steel, there being thus formed the desired openings surrounded by cutting edges. Dies manufactured in this manner are relatively expensive, since the operation is necessarily slow and requires highly skilled workmen. The present invention has as an object the production of dies made up of separate units readily formed, accurately assembled in the chosen design and securely maintained in position, all the operations being of such a character as to permit them to be performed rapidly by workmen having little experience. In the attainment of this object, die-elements, as punches sharpened to furnish cutting edges, are formed to correspond to each unit of the design or pattern to be reproduced and these elements, and such encircling die-elements as frames or knives, are arranged upon a support in accordance with the pattern. To each element is applied a force acting to retain it in the relation in which it was arranged. Then the elements are secured together in the relations established by the pattern as by metal, which may be poured upon the support into contact with said elements. This molten metal, which preferably has a relatively low melting point as compared with that of the material of the elements themselves, upon hardening locks the parts together permanently in the design in which they were disposed on the support, with the cutting edges of the elements projecting beyond the surface of the metal. The retaining force is preferably magnetic, the support being of magnetic material. This force is easily withdrawn by cutting off the magnetizing current, thus permitting the arrangement of the elements, and, when applied, fixing them in position without displacement. To avoid too quick and uneven chilling of

the molten metal, I prefer to heat the support. My method disclosed herein involves the production of the punch elements from tubes which are heated and subjected to pressure upon a form, these elements or punches being supported in the desired relation in a frame, and secured by the introduction of molten metal, as already indicated. For some transverse contours of the punches, such a single swaging operation may be sufficient before the elements are sharpened, assembled and secured. But when, for example, a punch includes abrupt angles, a succeeding operation may be desirable, a form being forced into the punch to change its contour. It may at the same time create a taper or otherwise alter the form of the punch longitudinally, giving a clearance for the discharge of the cut material. It is to be understood that, while with punches thus made and assembled it is desirable to retain them magnetically upon their support and to heat said support, these steps are not essential to this phase of the invention.

The accompanying drawings illustrate particular means for performing the steps of my invention.

In Fig. 1 is shown in perspective an apparatus in which tubes may be swaged to punch-form;

Fig. 2 illustrates in perspective a form for use in connection with the apparatus of Fig. 1;

Fig. 3 is a transverse section through the form and a portion of the swaging apparatus, taken on the line III—III of Fig. 1;

Fig. 4 is a perspective view of the blank produced by the swaging operation;

Fig. 5 is a similar view of a portion of a press employed for perfecting the form of the blank;

Fig. 6 is a section on the line VI—VI of Fig. 5;

Fig. 7 shows in perspective the blank of Fig. 4 after it has been operated upon by the apparatus of Figs. 5 and 6;

Fig. 8 is a perspective view of a heater which may be employed for preparing the tubular stock for swaging;

Fig. 9 illustrates in perspective the retain-

ing support, on which the punches are assembled and set in their securing frame, parts being broken away; and

Fig. 10 is a like view showing the cut-out die after the metal has been poured and the surrounding knife associated with it.

In carrying out the invention, a maker of cut-out or other combination dies would be provided with sections of steel-tubing of various diameters and corresponding in length to the punches to be made, and with their walls of appropriate thickness. One of these sections is shown at T in Fig. 2 of the drawings. For each size and transverse contour of punch to be manufactured, there would be a corresponding form 10 to act within the tube, and opposite swaging blocks 12 and 14 (Fig. 1) to act upon the outside. The blocks have opposite recesses, which are the complements of the opposite sides of the form 10. They are respectively held removably upon an abutment 16 fixed upon a base 18, and a slide 20 traveling in ways 22 extending horizontally above the base. Fulcrumed upon the base, at the extremity of the slide 20, is an eccentric-lever 24, acting to force said slide toward an abutment 16. The form 10 is mounted upon a handle 28 and is presented to the blocks 12 and 14 at the correct height by a slotted rest 29, on which the handle is supported. In the handle are opposite depressions 30, 30 to receive the edges of the rest 29 at the sides of the slot. This engagement insures the correct presentation of the tube upon the form longitudinally of the block-recesses. A rest 32, for the outer portion of the handle, is situated near the edge of the base and has a shank upon which is a thread, it being thus capable of adjustment by a nut 34 engaging the thread and contacting with the upper surface of the base. It may be retained in the chosen position by a set-screw 36 threaded through the side of the base and contacting with the shank. This adjustment provides for leveling the form and tube horizontally. A spring-pressed plunger 38, movable through the face of the block 12, bridges the space between this and the companion block when the work is in place, and prevents accidental upward displacement of the form and tube. Before the swaging operation, the tube-section which is to be operated upon is preferably heated in a furnace 41, this appearing in Fig. 8 as of the electric type. The form 10 is introduced into the hot tube, and positioned upon the rests 29 and 32 between the recesses of the blocks 12 and 14. At this time, the cam-lever 24 is so turned that the slide 20 may be withdrawn. Then the lever is swung to force the cam-portion against the slide and the block 14 into engagement with the tube, which is thus pressed into shape between the opposite sides of the form and the complementary walls of the recesses. Upon removing

the form from the press, it is drawn from the resulting blank *b* (Fig. 4), this separation being conveniently effected by engagement of the inner edge of the blank with a member 39 fixed to the base 18 and having a V-groove in which the form may be placed. This member also provides a rest for the form and its handle 28 when not in active use.

The blank *b*, as illustrated, has three comparatively abrupt angles *a*, which, at the inside where the cutting edge is to be, may not be sharply enough outlined by the swaging operation. In such a case, the contour may be perfected, or the form otherwise changed, by the apparatus of Figs. 5 and 6. There is illustrated here a base 40, upon uprights 42, 42 of which is mounted a vertically sliding cross-head 44 reciprocated by power mechanism (not illustrated). The base carries a removable holding device or fixture 46, which includes a stationary recessed wall 48 and an opposite recessed wall 50. The recess furnished between the two walls generally resembles the transverse contour of the blank *b* which is to be received, though, as its function is merely that of retaining the blank to receive the action of a forming tool, the correspondence need not be exact. At 52, ledges projecting in from the bottoms of the walls serve to support a blank to be operated upon, while overhanging plates 54, secured upon the tops of the walls, retain said blank against upward displacement. The wall 50 is shown as pivoted at 56 upon the companion wall, to permit it to be swung clear thereof, thus providing for the introduction of the blank. A cam-lever 58 is fulcrumed upon the base 40 at the outer side of the wall 50, to apply clamping pressure to this. Depending from the cross-head 44, and alined with the space between the recessed walls 48 and 50, is a forming tool 60. The transverse contour of this tool is preferably precisely that which the punch being made is to possess. It is tapered gradually, its sides converging downwardly, so that it will not only perfect the form of the blank into which it is forced, but will also incline the walls of this between the opposite ends, providing the necessary draft for the discharge of the cut pills. In the employment of this forming apparatus, the wall 50 is freed by the lever 58, raised, and a blank *b* placed upon the ledges 52. The movable wall is thereupon returned to its normal position and clamped by the lever. Upon putting the press into operation, the tool 60 descends through the opening between the cover-plates 54, 54, into the blank *b*, and forces its way through this, giving the interior its final form. When the cross-head rises, the tool 60 is withdrawn, at which time the formed blank *B*, particularly illustrated in Fig. 7, is prevented from following the tool by the overhang of the plates 54. lease of the lever and elevation of the wall 50 frees the blank.

When the blank B has been sharpened at its smaller extremity, it furnishes a completed punch P. Five of these punches appear in Figs. 9 and 10. These may be assembled in a design within a surrounding non-cutting frame, this arrangement producing a cut-out portion only in the stock operated upon; a

knife may furnish the frame, so a piece of stock with a contained design may be cut by a single operation; or the punches in a frame may be mounted within a knife. In the last instance, the result attained is the same as when the punches and knife are per-

15 manently secured to one another, except that different assemblages of punches may be used with the same knife. The cut-out die separable from the knife is what is illustrated in Figs. 9 and 10. In making such a die as is

20 there shown, the punches P are placed upon a support in the form of a plate 62 and surrounded by a frame F of steel, this frame being of considerably less height than the

25 punches, to allow for the cutting action of the latter. In the frame, the punches are

30 arranged in accordance with a perforated pattern or templet. Within the support, which is of iron, are mounted coils, one 64 being a

35 magnetizing coil, and one or more 66 being heating coils or units. The latter are shown as in close proximity to the upper supporting surface of the plate, where the assembled die rests. Electric current is passed through

40 the coil 64, magnetizing the support and thus exerting upon the punches and frame a force which retains them firmly in the relation

45 which has been determined by the templet. With this magnetic retaining means, there is

50 no danger of displacing the die-elements in effecting their retention. Current is also passed through the coil or coils 66, so the support and die-elements are heated. Molten

55 metal is now poured within the frame upon the support, surrounding the punches to sub-

stantially the top of the frame. The metal employed is preferably a relatively soft and readily fusible alloy. I have found a mix-

60 ture of approximately equal parts of lead and tin suitable for this purpose. Solder and type-metal may also be used. The heat of the support and die-elements allows the

65 metal to flow uniformly without premature chilling, which would tend to make it uneven in texture and weaken the attachment of the

70 elements. When the metal, which appears at M in Fig. 10, has set, the cut-out portion d has been completed, and the current is cut off from the coil 64, so the die d may be re-

75 moved from the support. No further form-

ing or sharpening of the operating edges of

80 the punches is necessary. If a piece of stock of a particular form and containing the cut-

85 out design is to be produced at the same time as said design, the frame F is provided with

opposite lugs f adapted to enter corresponding recesses in the pressure-receiving edge of a surrounding knife D having a cutting edge of the desired contour. Securing screws and pins pass through openings in the lugs into registering openings in the body of the knife. The cut-out die d is thus made separable from the knife D, and other combinations of an external outline and contained design may be arranged.

Throughout the various operations of making the die-elements and assembling them in the chosen design, it will be seen that little skill is called for, the forming and arranging being mechanically determined, and that but a short time is necessary for the performing of any step of the method. The resulting dies are strong and are accurate in their outlines.

Having described my invention, what I claim as new and desire to secure by Letters Patent of the United States is:

1. The method of making cutting dies from patterns made up of separate design-units, which consists in forming a cutting element corresponding to each design-unit, sharpening each element to furnish a cutting edge having the contour of a unit of the design, arranging the cutting elements upon a support under the guidance of the pattern in accordance with the design to be cut, applying to each cutting element a force acting to retain it as arranged upon the support, and securing the cutting elements together in the relation established by the pattern to form the die.

2. The method of making cutting dies from patterns made up of separate design-units, which consists in forming a cutting element corresponding to each design-unit, sharpening each element to furnish a cutting edge having the contour of a unit of the design, arranging the cutting elements upon a support of magnetic material under the guidance of the pattern in accordance with the design to be cut, magnetizing the support to retain the cutting elements in the relation established by the pattern, and securing the cutting elements together by metal while they are thus retained by the magnetized support and with their cutting edges projecting beyond the adjacent surface of the retaining metal.

3. The method of making cutting dies from patterns made up of separate design-units, which consists in heating a tube and pressing it over a form to furnish a punch corresponding to each design-unit, sharpening each punch to produce a cutting edge having the contour of the design-unit, arranging the sharpened punches upon a support under the guidance of the pattern, applying to each punch a force acting to retain it as arranged upon the support, surrounding the punches upon the support with a frame, and securing

the punches and frame together to form the die.

4. The method of making cutting dies from patterns made up of separate design-units, which consists in heating a tube and pressing it over a form to furnish a punch corresponding to each design-unit, sharpening each punch to produce a cutting edge having the contour of the design-unit, arranging the sharpened punches upon a support under the guidance of the pattern and with a surrounding cutting knife, and securing together by metal the punches and knife as positioned upon the support in accordance with the pattern to form the die, the cutting edges of the punches and knife projecting beyond the adjacent surface of the retaining metal.

5. The method of making cutting dies from patterns made up of separate design-units, which consists in heating a tube and pressing it over a form to furnish a punch corresponding to each design-unit, sharpening each punch to produce a cutting edge having the contour of the design-unit, arranging the sharpened punches upon a support under the guidance of the pattern, applying to each punch a force acting to retain it as arranged upon the support, surrounding the punches upon the support with a frame, and pouring within the frame about the punches a metal having a low melting point as compared with that of the punch-material, said metal securing the punches and frame together with the cutting edges of the punches projecting above the surface of the metal.

6. The method of making cutting dies from patterns made up of separate design-units, which consists in heating a tube and pressing it over a form to furnish a punch corresponding to each design-unit, sharpening each punch to produce a cutting edge having the contour of the design-unit, arranging the sharpened punches upon a support under the guidance of the pattern, applying to each punch a force acting to retain it as arranged upon the support, surrounding the punches upon the support with a frame, pouring within the frame about the punches a metal having a low melting point as compared with that of the punch-material, said metal securing the punches and frame together with the cutting edges of the punches projecting above the surface of the metal, and heating the support and punches prior to the pouring to a temperature insuring a uniform flow of the retaining metal about the punches.

7. The method of making dies, which consists in heating a tube, swaging the tube over a form to produce the transverse contour of the punch-element of a die, forcing a form through the punch to change its contour, placing the punch and a surrounding frame upon a support, and filling the space between the punch and frame with metal.

8. The method of making dies, which consists in heating a tube, swaging the tube over a form to produce the transverse contour of the punch-element of a die, forcing a form through the punch to change its contour, placing the punch and a surrounding frame upon a support, applying to the punch and frame a force acting to retain them in place upon the support, and filling the space between the punch and frame with metal.

9. The method of making dies, which consists in heating a tube, swaging the tube over a form to produce the transverse contour of the punch-element of a die, forcing a form through the punch to perfect its contour, placing the punch and a surrounding frame upon a support, heating the support, and pouring molten metal upon the support within the frame about the punch.

In testimony whereof I have signed my name to this specification.

ALBERT R. BRADEN.
